UNITED STATES PATENT OFFICE.

FRANK J. SPRAGUE, OF NEW YORK, N. Y.

ELECTRIC RAILWAY.

SPECIFICATION forming part of Letters Patent No. 340,684, dated April 27, 1886.

Application filed November 24, 1885. Serial No. 183,893. (No model.)

To all whom it may concern:

Be it known that I, FRANK J. SPRAGUE, of New York city, in the county and State of New York, have invented a certain new and useful Improvement in Electric Railways, of which the following is a specification.

In my Patent No. 318,668, dated May 26, 1885, is set forth a method of braking an electric-railway train by increasing the counter electro-motive force of the dynamo-electric machine, which normally acts as a motor propelling the train until the same exceeds the initial electro-motive force on the line, whereby the machine becomes a generator, and the energy of the train is converted into current on the line. In employing this method, as is set forth in said patent, when the machine is running as a generator, the diminution of speed of the armature tends to diminish its electro-motive force, which is counter to the electro-motive force on the line, and it is therefore necessary to keep on increasing the field-magnet strength, so as to still maintain this electro-motive force above that of the line. When, however, the limit of regulation of the field is attained, this electro-motive force will begin to fall, and will equal or fall below the initial. It is then necessary to bring into operation other means for continuing to brake the train in order to bring it to a full stop. I accomplish this by providing the machine with a local circuit, in series with its armature, which is closed and the main armature-circuit broken, while the field-circuit (the machine being shunt-wound) is still left in connection with the line. There is thus formed a braking-generator with its field supplied from the line-current and its armature supplying a local circuit. The energy of the moving train is expended in this local circuit, and the train is stopped. The local circuit may include a suitable resistance, or it may include the operating magnet or magnets of an electro-magnetic brake, which will be thrown into operation when the circuit is closed. This latter feature forms no part of my present invention, but is included in another application for Letters Patent of even date herewith. The current expended in the local circuit may be regulated by adjusting the resistance in said circuit, or, preferably, by regulating the field-magnet of the

machine. The resistance in the local circuit is preferably the usual armature-circuit resistance, the circuit being arranged to include this. The field-magnet being supplied from an independent source, (the line,) its strength is independent of the armature-current and of the rate of motion of the train, and the current in the local circuit can therefore be made to depend upon the strength of the field, which, as stated, is regulated, preferably, by an adjustable resistance.

My invention is illustrated in the annexed drawings, in which Figure 1 is a plan view of a truck of an electric-railway car with the machine running as a motor, the circuits and regulating apparatus being shown in diagram; and Fig. 2 a similar view showing the same machine running as a braking-generator.

A is the truck of a car. B is the armature, and C the field-magnet, of a dynamo-electric machine, which normally runs as a propelling-motor, but is convertible into a braking-generator, as described. By cog-wheels D D motion is communicated from the armature-shaft of the machine to the driving-axle E of the car when the machine is a motor, or from the axle to the shaft when it is a generator.

E F are the main rails of the track, forming one side of the circuit, and G is an intermediate rail forming the other side.

H is a generator supplying current to the railway. Contact-rollers I I run on the intermediate rail, while the connection to the main rails is by brush or spring a, resting on axle E and supported in any suitable manner.

The various switching and regulating devices are shown, for convenience, as separate from the car. It will of course be understood that they are suitably placed upon or within the same.

K is the regulating apparatus for the armature and field circuits, which is such as is set forth in my Patent No. 321,150, dated June 30, 1885. In this apparatus b b are resistance-coils for the field-circuit, connected with short contact-blocks c c and long block d, and e e are coils for the armature-circuit connected, with short blocks f f and long block g. Pivoted arms h h' travel on the contact-blocks.

L is the switch for throwing the armature from the line to the local circuit. It consists of two sets of three blocks each, i i' i'' and k k'

k^2 , and two insulated contact-arms, l and l' , traveling on said blocks.

M is a reversing-switch for the armature-circuit.

- 5 The circuits in Fig. 1 are as follows: from brush or spring a by wire 1 to arms h and h' of switch K , where the circuits divide, the field-circuits being by resistance-coils b to long block d , wire 2 to field-magnet, and wires 10 3 3 to contact-rollers I I' , and the armature-circuit is by h to long block g , wire 4 to block e^2 of switch L , arm l to i' , wire 5 through reversing-switch M and wire 6 to motor-commutator, back to switch M by wire 7, and by 15 wire 8 to block k' of switch L , arm l' to k , and wire 9 to wires 3 3 and the contact-rollers.

As shown here, the machine is running as a motor in its ordinary manner, with no resistance in its armature-circuit, and it is regulated by varying the number of resistance-coils b in field-magnet circuit.

In Fig. 2 the construction and arrangement of apparatus are the same; but here the machine is shown as converted into a generator 25 and running on its local circuit. This is accomplished in the following manner: It being desired to stop the car or train, arms h h' of switch K are turned so as to remove resistance-coils b from circuit, thereby strengthening 30 the field and increasing the counter electro-motive force in the armature-circuit. This is continued until the counter electro-motive force overcomes the initial and the energy of the train's momentum is thrown in current 35 upon the line; but, as stated, the slowing down of the train causes a tendency to decrease the counter electro-motive force, so when the field is strengthened as much as it can be the counter electro-motive force will 40 continue to decrease, the machine will again become a motor running at slow speed, and the train would not be stopped. When, however, the electro-motive forces become equal, which is shown by an indicator, S , 45 of quantity and direction of current, switch L comes into play, and the change of its position to that of Fig. 2 changes the connection of the armature from the line to a local circuit, as follows: from one commutator-brush by wire 6 to switch M , wire 5 to block i' of switch L , arm l to i , wire 10 to switch K , 50 through coils e to arm h , wire 11 to block k^2 of L , l' to k' , wire 8 to switch M , and wire 7 to other commutator-brush. The local circuit 55 thus includes the resistance e , and the energy expended therein is regulated by adjusting such resistance; or it may instead be regulated by adjusting the field-circuit resistance b without affecting the armature-circuit 60 resistance, the field remaining connected with the line, and supplied with current therefrom independent of the condition of the armature.

The coils of the resistance in the armature-circuit are made of such size that they can 65 carry all the current which passes in starting

the motor, and therefore they cannot be injuriously affected by the braking-current.

The indicator S shows when the initial and counter electro-motive forces are equal, and 70 also may be employed to show the amount of the armature-current when the machine is running as a motor, and of the braking-current when it is a generator.

It is evident that separate switches may be 75 used to brake the main armature-circuit and close the local circuit; but the single-motion switch is of course preferable.

While I have described my invention wholly 80 with reference to a simple shunt-wound machine, it is evident that it is equally applicable to a compound machine having its main field-coils in shunt relation to the armature and other field-coils in series with the armatures.

What I claim is—

1. The combination, with a car or train of cars on an electric railway, of a braking-generator operated by the movement of said car or train, having its main field-magnet coils 90 supplied from the line and its armature supplying a local circuit, and an adjustable resistance in said local circuit, substantially as set forth.

2. The combination, with a car or train of 95 cars on an electric railway, of a braking-generator operated by the movement of said car or train, having its main field-magnet coils supplied from the line and its armature supplying a local circuit, and means for regulating the strength of said field-magnet, substantially 100 as set forth.

3. The combination, with a car or train of cars on an electric railway, of a braking-generator operated by the movement of said car or train, having its main field-magnet coils 105 supplied from the line and its armature supplying a local circuit, and an adjustable resistance for regulating the current supplied to said main field-magnet coils, substantially as 110 set forth.

4. The combination, with a car or train of cars on an electric railway, of a braking-generator operated by the movement of said car or train, having its main field-magnet coils 115 supplied from the lines, and its armature supplying a local circuit, a resistance in said local circuit, and means for regulating the strength of said field-magnet, substantially as set forth.

5. The combination, with a car or train of 120 cars on an electric railway, of a braking-generator operated by the movement of said car or train, having its main field-magnet coils supplied from the line and its armature supplying a local circuit, an adjustable resistance 125 in said local circuit, and an adjustable resistance for regulating the current supplied to said main field-magnet coils, substantially as set forth.

6. The combination, with a car or train of 130 cars on an electric railway, of a dynamo-electric machine having its armature-shaft con-

nected mechanically with a driving-axle, and its main field-magnet coils permanently connected electrically with the line, means for regulating the strength of said field-magnet, a local armature-circuit, and means for connecting the armature electrically either with said local circuit or with the line, substantially as set forth.

7. The combination, with an electric rail-way, of a dynamo-electric machine adapted to

be used either as a propelling-motor or a braking-generator and a device indicating strength and direction of current in the armature-circuit thereof, substantially as set forth.

This specification signed and witnessed this 15
7th day of November, 1885.
